BAG HANDLING APPARATUS

Filed Feb. 9, 1929

By *Watson E. Coleman*

UNITED STATES PATENT OFFICE

EDWARD CANUEL, OF MOLSON, WASHINGTON

BAG-HANDLING APPARATUS

Application filed February 9, 1929. Serial No. 338,759.

This invention relates to bag handling apparatus, and more particularly to apparatus for use in handling sacks of grains or other similar material.

5 An important object of the invention is to produce a device of this character which will enable the manipulator to secure a very firm grip upon the grain sack without the necessity of digging his fingers into the sack 10 or attempting to handle the sack by engagement with one end thereof.

A further object of the invention is the provision of a device of this character which may be left permanently applied to the 15 hands of the operator and yet may be shifted from the position which it occupies when in use to a position where it will not interfere with use of the hands in gripping other objects as, for example, the handles of a 20 truck upon which the sacks have been placed.

A further object of the invention is to provide a device of this character which may be very readily and cheaply manufactured, which will be durable and efficient in 25 service and a general improvement in the art.

These and other objects I attain by the construction shown in the accompanying drawings, wherein for the purpose of illustration is shown a preferred embodiment of my invention and wherein:—

Figure 1 is a top plan view showing bag handling apparatus constructed in accordance with my invention;

35 Figure 2 is a bottom plan view of the hand element thereof;

Figure 3 is a longitudinal sectional view on the line 3—3 of Figure 1.

Referring now more particularly to the 40 drawings, the numeral 10 generally designates a substantially rectangular slab of relatively stiff material, such as leather or the like, having embedded therein the heads of spikes 11, which spikes project through one 45 face of the slab. This slab should be of a length to extend from the wrist of the wearer to a point adjacent the outer ends of the fingers, and upon the rear face thereof has secured thereto at one end pairs of securing 50 straps 12 adapted to engage about the wrist

of the wearer and adjustable, as at 13, so that they may tightly engage with the wrist. At its opposite end upon its rear face, a loop 14 is secured to the slab and is adapted to loosely receive the ends of the fingers of the wearer. This loop is so disposed that it lies outwardly of the knuckles of the hand and is sufficiently loose to enable the fingers to be completely disengaged therefrom while the straps 12 still confine the wrist. With the fingers disengaged from this loop, the hand may be employed to engage the handles of a truck or in any other work without any serious interference from the slab.

The inner or wrist end of the slab has secured thereto the smaller end of a trunco-triangular cuff element 15, which is preferably formed of flexible leather, and has secured to its inner face, adjacent its base edge, one element 16 of a snap fastener. In combination with a structure of this character, I provide a sleeve guard 17 of the usual type, this guard being in the form of a tube through which the arm may be passed and having the upper end thereof split for a short distance, as at 18. The edges of this split are drawn together by an elastic web 19, so that the sleeve guard will secure itself in adjusted positions. This sleeve guard is provided with the second element 20 of the snap fastener for coaction with the element 16 of the cuff.

In use of apparatus of this character, which will, of course, be provided in pairs, the sleeve guards are pulled in position over the arms and the grippers are then secured in position upon the wrists by the straps 12, with the back faces of the slabs 10 against the palms of the hands. The fingers are slipped through the loops 14 when engaging a sack. Attention is directed to the fact that the teeth will enter in the sack and obtain a very good grip thereon and since the slabs are supported from the wrists, the only necessary strain upon the hands is that required to maintain the engagement of the teeth. All lifting can be done from the wrists, thus preventing excessive tiring of the hands. When other work is to be done, the fingers can be slipped from the loops 14, thus freeing the hand suf- 100

ficiently to enable this work to be accomplished without the complete removal of the grippers.

A convenient means for producing the spike slab is to simply employ the leather body and drive headed spikes therethrough and then to back this slab with a rubber sheeting 10a which may be cemented or otherwise secured thereto. This sheeting 16 serves to prevent the spikes from being forced out of the slab and to prevent the sweat of the hands from passing into the leather. This latter feature is important since bag handling is strenuous labor and the 15 perspiration would soon have a tendency to rot the leather and to cause the spikes to loosen therein.

Since the construction hereinbefore set forth is capable of a certain range of change 20 and modification without materially departing from the spirit of the invention, I do not limit myself to such specific structure except as hereinafter claimed.

I claim:

25 1. In bag handling apparatus and in combination, a palm engaging member comprising a relatively stiff body having spikes extending from the outer face thereof, wrist encircling straps secured to the inner face 30 of the member at one end thereof, a wrist guard secured to one end of said body, a loop at the opposite end of the body at the inner face thereof adapted to receive the fingers of the wearer, the loop being of a size permitting 35 disengagement of the fingers therefrom while the body is secured to the wrist of the wearer through said straps, a forearm receiving tube, means for pivotally connecting said tube to the 40 wrist guard, said forearm receiving tube being split for a portion of its length and an elastic strap secured to the split portions of said tube for yieldably urging the ends together.

2. In bag handling apparatus and in combination, a palm engaging member comprising a relatively stiff body having spikes extending from the outer face thereof, wrist encircling straps secured to the inner face of the member at one end thereof, a loop at the 50 opposite end of the body at the inner face thereof adapted to receive the fingers of the wearer, the loop being of a size permitting disengagement of the fingers therefrom while the body is secured to the wrist of the wearer through said straps, a forearm receiving tube, means for connecting said tube to the first mentioned end of the body, comprising a flexible leather guard secured to 55 said end of the body and adapted to protect the wrist of the wearer, said forearm receiving tube being split for a portion of its length and an elastic strap secured to the split portions of said tube for yieldably urging the ends together, and coacting elements of a 60 fastener carried by the inner face of said

guard and the outer face of said arm receiving tube for pivotally and removably connecting the tube to said guard.

In testimony whereof I hereunto affix my signature.

EDWARD CANUEL.
